UNITED STATES PATENT OFFICE.

ROBERT SAMUEL RINKER, OF RINKERTON, VIRGINIA.

GRAIN-SEPARATOR.

SPECIFICATION forming part of Letters Patent No. 738,699, dated September 8, 1903.

Application filed May 7, 1901. Serial No. 59,172. (No model.)

To all whom it may concern:

Be it known that I, ROBERT SAMUEL RINKER, a citizen of the United States, residing at Rinkerton, in the county of Shenandoah and State of Virginia, have invented a new and useful Grain-Separator, of which the following is a specification.

My invention is an improved grain-separator; and it consists in the peculiar construction and combination of devices hereinafter fully set forth and claimed.

The object of my invention is to provide a simple and improved machine which is effective in separating various kinds of grain and is peculiarly adapted for separating cockle and garlic seeds from wheat or other grain, as well as for separating various grains.

In the accompanying drawings, Figure 1 is a perspective view of a grain-separator embodying my improvements. Fig. 2 is a detail transverse sectional view of the same. Fig. 3 is a similar view taken on a plane at right angles to that of Fig. 2.

My invention in its simplest form comprises an endless traveling belt or apron 1, which is inclined at a suitable angle transversely, receivers 2 under the belt or apron, and a feeder to discharge seeds on the latter near its upper side and near one end of its upper lead, so that the seeds in rolling more or less slowly, according to their shape, will be discharged from the endless traveling belt or apron into the receivers under the same, the more nearly spherical seeds or grains being discharged first, owing to the greater facility with which they roll down the inclined surface of the endless traveling apron or belt which forms the separating element, and those seeds or grains which depart from the spherical form rolling more slowly down the inclined surface of the said endless traveling separating element, and hence being carried farther thereby before they are discharged therefrom into appropriate receivers. Thus cockle, which is substantially spherical in form, will be first discharged from the inclined traveling separating element. Wheat, which is less spherical in form than the cockle, will be next discharged. Rye, which is more cylindrical in form and more flattened on opposite sides than wheat, will be next discharged from the inclined traveling separating element, and

oats, which are more elongated than rye and more nearly approach the conical form, will be discharged from the inclined traveling separating element subsequently to the rye.

In the form of my invention here shown I provide an inclined supporting-frame 3, which may be of any suitable construction, and on the same I mount a series of endless traveling transversely-inclined separating elements which extend transversely of the frame and are disposed at a suitable distance apart and one below another throughout the series. A roller 4 is mounted in suitable bearings 5 on one side of the frame and is common to all of the belts or aprons 1. A handle 6 is here shown for rotating said roller and hence causing the said belts or aprons to move in the direction indicated by the arrow. Each of the belts 1 passes over an independent roller 7, one of which is provided for each of said belts or aprons, the said independent rollers 7 being mounted in suitable movable bearings 8 on the side of the frame opposite the roller 3, and the said frame being provided with suitable brackets 9, in which operate set-screws 10 for adjusting said movable bearings 8, hence enabling the rollers 7 to be adjusted as may be required to keep the belts 1 stretched to the requisite tension.

The receivers 2 are inclined troughs disposed side by side in the frame 3 and under the endless traveling separating belts or aprons. Suitable receptacles 11 should be placed at the lower discharge ends of said troughs.

A hopper 12 is disposed above the upper side of the frame 3, at one side thereof, and from the bottom of the said hopper leads a feed-tube 13, provided with a series of spouts 14, each of which discharges on the upper lead of one of the endless traveling separating belts or aprons near the inner end and near the upper side thereof. In the lower side of said feed-tube and in the throats of said spouts 14 are suitable screens 15, which vary in the size of their meshes and in the practical operation of my invention effect a partial separation of the grains before the same are fed onto the endless traveling inclined separating belts or aprons. A suitable seed-valve 16 is provided at the upper end of the feed-tube 13 for regulating the flow of the

seeds or grains from the hopper to the said feed-tube.

A suitable scraper, as at 17, Fig. 2, may be employed to operate on the separating belts 5 or aprons to scrape adhering seeds and particles therefrom and prevent the same from being dropped from the under sides of the separating belts or aprons onto the receivers.

While my improved separator may be used 10 in any manner desirable for the separation of grains or seeds, as in mills or the like, it will be found particularly useful when run in connection with a threshing-machine.

Having thus described my invention, I 15 claim—

1. In a separating-machine, the combination of a supporting-frame, a plurality of endless traveling laterally-inclined separating-belts disposed transversely on the frame at a suit- 20 able distance apart and one lower than another throughout the series, rollers to support and operate said separating-belts, having their bearings on the frame, one of said rollers being common to all of said separating-belts, means to feed the latter, and a plu- 25 rality of receiving-troughs, disposed side by

side and under said separating-belts, sub-stantially as described.

2. In a separating-machine, the combination of a supporting-frame, a plurality of endless traveling laterally-inclined separating-belts disposed transversely on the frame at a suitable distance apart and one lower than another throughout the series, rollers to support and operate said separating-belts, having their bearings on the frame, one of said rollers being common to all of said separating-belts, a feeder comprising a hopper, an inclined feed-tube leading therefrom and having spouts discharging onto said separating- 35 belts, said spouts having screens of appropriate mesh therein, and a plurality of receiving-troughs, disposed side by side and under said separating-belts, substantially as described. 40

In testimony that I claim the foregoing as 45 as my own I have hereto affixed my signature in the presence of two witnesses.

ROBERT SAMUEL RINKER.
